PLURAL PHASE RECLOSED CIRCUIT BREAKER

James M. Wallace, East McKeesport, Pa., assignor
to Westinghouse Electric Corporation, East
Pittsburgh, Pa., a corporation of Pennsylvania

Application June 23, 1949, Serial No. 100,787

14 Claims. (Cl. 200—89)

1

This invention relates generally to plural phase automatic reclosing circuit breakers, and more particularly to a particular arrangement for locking such breakers in open circuit position on the occurrence of persistent overloads on the circuit.

When an overload occurs on but one phase of a polyphase circuit, it is desirable that only that phase of the circuit be opened in attempting to clear line-to-ground faults. However, if the condition causing the overload persists, as upon reclosing the overloaded phase one or more times, it is desirable to leave that circuit open for repair purposes, and it is then desirable that all phases of the circuit be held open.

Accordingly, one object of this invention is to provide a polyphase automatic reclosing circuit breaker with novel means permitting independent single-phase circuit opening in response to overloads, but operable in response to a predetermined number of closely successive operations in any particular phase to automatically maintain all phases of the circuit open.

Another object of this invention is to provide a multi-pole automatic reclosing circuit breaker of the type described, wherein each pole has an independent structure supplying its own energy for opening the circuit connected with that pole, and in response to a predetermined number of closely successive circuit opening operations of a single pole will automatically cause all poles to open and be maintained at open circuit position.

Another object of this invention is to provide a multi-pole automatic reclosing circuit breaker of the type described, wherein each pole has an independent structure supplying its own energy for opening the circuit connected with that pole, and in response to a predetermined number of closely successive circuit opening operations of a single pole will automatically cause all poles to open and be maintained at open circuit position, with the energy for so opening all poles obtained from energy stored during a manual circuit closing operation.

These and other objects of this invention will become more apparent upon consideration of the following detailed description of a preferred embodiment thereof, when taken with the attached drawings, in which:

Figure 1 is a longitudinal section view through the tank for a three-pole automatic reclosing circuit breaker embodying this invention, with the pole units and operating mechanism shown in elevation.

Fig. 2 is a top plan view of the circuit breaker

shown in Fig. 1 with the tank cover removed, and Fig. 3 is a transverse cross section view taken substantially on the line III—III of Fig. 1.

The embodiment of the invention illustrated on the drawings is a three-pole automatic reclosing circuit breaker mounted in a metal tank 2 having a closed bottom (not shown) and an open top, with a flange 4 at the top. The circuit breaker pole units and operating mechanism are all mounted on a transversely extending supporting plate 6 which is suspended from the top of tank 2 by a plurality of angular supporting brackets 8, welded or otherwise secured to supporting plate 6, and resting on the top edge and flange 4 of tank 2. Supporting plate 6 is adapted to be secured in the position shown in Fig. 1 by securement of a cover 10 to tank 2. Cover 10 has an internal lip 12 adapted to fit inside tank 2, and an external flange 14 adapted to seat on flange 4 of tank 2 and on supporting brackets 8, with packing material 13 being interposed between flanges 4 and 14 at least in the spaces between supporting brackets 8.

Three pole units 16, 18 and 20 are illustrated as being suspended from supporting plate 6, with each unit being suspended by a pair of rods 22, preferably of insulating material, such as a molded insulating material, which are secured to supporting plate 6 as by bolts 24 at the upper ends of rods 22, and at their lower ends are secured to a solenoid coil structure 26. Each solenoid coil structure 26 is adapted to support an interrupter chamber 30, for example, as by one or more supporting plates 28 joining the coil structure and interrupter chamber 30. It will thus be observed that pole units 16, 18 and 20 are unitarily supported with supporting plate 6, and all may be removed from tank 2 as a unit, by merely removing tank cover 10 and lifting supporting plate 6 upwardly.

The pole units 16, 18 and 20 are identical in form, and are substantially identical with the pole unit of the single pole automatic reclosing circuit breaker shown in the patent to J. M. Wallace No. 2,333,604, issued November 2, 1943, to the same assignee as this invention. Accordingly, for a more detailed description of the pole units and their mode of operation, reference is hereby made to the above-mentioned Wallace patent. In general, each pole unit includes the solenoid coil structure 26 previously mentioned, and interrupter chamber 30, with the latter comprising a tube 32 of insulating material, such, for example, as fiber or the like, having a top cap 36 and a bottom cap 34 secured on opposite ends of

the tube, for example, as by being threaded thereon. A fixed contact 38 is carried by bottom cap 34 of the interrupter chamber within tube 32, and it is adapted to be engaged by a movable contact 40 mounted on the lower end of a movable contact rod 42. Contact rod 42 extends upwardly through a central opening in top cap 36 of the interrupter chamber, and is provided with an insulating sleeve 44 to insulate the rod from top cap 36.

As described in the above-mentioned Wallace patent, interrupter chamber 30 is designed to be substantially entirely enclosed at least when the circuit is being interrupted therein, so that movable contact 40 need be separated from fixed contact 38 but a relatively small amount by the actuating mechanism, because thereafter the pressure generated by the arc formed by such initial contact separation will act on movable contact 40 in a piston-like manner to increase its separation from fixed contact 38 until the arc is finally extinguished.

Contact actuating rod 42 extends upwardly through a central opening in coil structure 26, and at its upper end is joined to a pair of connecting links 48, preferably of insulating material such as fiber or the like, as by a pivot pin 46, with these links in turn being pivoted at 50 to an actuating lever 52 in the case of pole units 18 and 20, while in the case of pole unit 16 connecting links 48 are pivoted to an actuating lever 54. Both actuating lever 52 and actuating lever 54 are pivotally mounted on a pivot shaft 56, which extends for a limited distance transversely of the circuit breaker tank above supporting plate 6, all for a purpose to be described.

In order to provide for limited initial separation of movable contact 40 from fixed contact 38, a solenoid core 58, which is generally circular in section, closely slidably fits in a cylindrical bore provided within solenoid coil structure 26, and core 58 has a central opening closely slidably fitting on actuating rod 42. At its upper end core 58 is adapted to move between cylindrical bore 60 and an actuating sleeve 62 mounted on actuating rod 42, and having a head 64 at its upper end which limits downward movement of actuating sleeve 62.

The circuit through the breaker may now be traced from the points where it enters tank 2 through insulating bushings 156 provided in cover 10, with the circuit to pole unit 16 for example entering by way of a conductor 158 to its solenoid coil structure 26, and thence by a conductor 160 to its contact actuating rod 42, through the contacts 40, 38 and by way of a conductor 162 to another bushing 156. Similarly, pole unit 18 is supplied from a bushing 156 by a conductor 164 leading to its solenoid coil 26, then by a conductor 166 to its contact actuating rod 42, through its contacts and out by way of a conductor 168 and another bushing 156. The supply to pole unit 20 is from a bushing 156 by a conductor 170 to its solenoid coil 26, and exits by way of a conductor 172 to another bushing 156. Small bushings 174 of insulating material are provided in supporting plate 6 where each of the bushing conductors passes through this plate. While bushings 156 and 174 may be of any desired insulating material, they are preferably of a material such as porcelain, which is of a weather-proof nature, particularly bushings 156.

It will thus be observed that the solenoid coil 26 of each of the pole units is connected in series in the circuit through that unit, so that upon the

occurrence of an overload in the circuit of that particular unit its solenoid coil 26 will attract its core 58 and move it upwardly. Such upward movement of a solenoid core 58 is delayed, however, by the dashpot action of the core in cylindrical bore 60, so that opening of the contacts will be delayed until core 58 has moved upwardly far enough so that its bottom wall engages the lower end of actuating sleeve 62. As core 58 continues its upward movement, actuating sleeve 62 will be lifted so that its head 64 engages shoulder 66 on actuating rod 42 to lift the rod and its contact 40, and thus separate the latter from fixed contact 38 to strike an arc. The arc thus struck will then be extinguished within interrupting chamber 30 in the manner previously described, and it will be observed that movable contact 40 is free to be moved by the pressure generated within the interrupter chamber, beyond the point it is moved by solenoid core 58, because of the lost motion between the core and contact rod 42.

After a circuit opening operation, the movable contact 40 of each pole unit is biased to automatically reclose the circuit by means which will be described hereinafter, and since it is desirable to delay the closing operation, an arrangement is provided for conforming at least the initial part of contact closing movement to downward travel of solenoid core 58 which is, of course, delayed by its dashpot action in cylindrical bore 60. To this end, there is provided a latch supporting plate 68 mounted on contact rod 42 just above the top of interrupter chamber 30, which pivotally supports at 70 a latch plate 78, with the latter having one opening freely receiving contact rod 42, and a second smaller opening 74 which is adapted to bind on a fixed latch rod 76, to releasably latch contact rod 42 at a plurality of open circuit positions. Latch plate 78 is biased in a counterclockwise direction as viewed in Fig. 1, by a coil compression spring 72 mounted on contact rod 42. During a circuit opening operation, any tendency of opening 74 in the latch plate to bind on rod 76 is prevented by clockwise rotation of latch plate 78 against its biasing spring 72. However, as soon as contact rod 42 starts to move downwardly to close the circuit, opening 74 in the latch plate will bind on rod 76 due to counterclockwise movement of latch plate 78 assisted by its spring 72, and accordingly the contacts will be latched at the open circuit position they attained when the circuit was interrupted, and will be released only when core 58 moves downwardly to engage the outer end of latch plate 78 and rotate it in a clockwise manner. The contact 40 will thus have its closing movement conformed with that of core 58 at least until the lower reduced end of latch rod 76 is reached, at which point opening 74 in latch plate 78 will be no longer effective to bind on such reduced portion of rod 76, and the final portion of contact closing movement will thus occur relatively quickly.

Each pole unit is also provided with its own mechanism for counting closely successive operations of the unit, and this means is also similar to that described in the previously mentioned Wallace patent, in that it includes a counting cylinder 80 mounted on top of the coil structure 26 of each pole unit, and a counting piston 82 slidably mounted in each cylinder 80. Each counting piston 82 has a plurality of upper reduced area ratchet portions 84 which are adapted to be engaged by the upper end of a substantially U-shaped pawl member 86, which has access to

the ratchet portions 84 by means of an opening cut in one side of cylinder 80. Pawl 86 has its bight portion longitudinally split to receive the upper end of contact actuating rod 42 and guide rod 88, so that the bottom leg of the ratchet seats on head 64 of actuating sleeve 62, and has an opening to slidably receive the pawl guide rod 88 fixed in position at the top of solenoid coil structure 26. Pawl 86 is biased to the position shown in Fig. 1 by a coil compression spring 90 mounted on guide rod 88.

It will be observed that each time actuating sleeve 62 is moved upwardly to separate the contacts of its pole unit, it will tilt pawl 86 into engagement with the upper ratchet portion of counting piston 82 and move the latter upwardly a predetermined amount. Inasmuch as the entire structure is adapted to be immersed in an arc extinguishing fluid, such as oil, which preferably fills tank 2 to a level nearly up to supporting plate 6, counting piston 82 is arranged so that such fluid is drawn into the lower end of counting cylinder 80 by means of a one-way check valve or the like (not shown), so that when the circuit recloses and pawl 86 resets to the position shown in Fig. 1, counting piston 82 remains at the position to which it was advanced for a definite time period. However, if the circuit breaker does not immediately reopen, counting piston 82 will slowly sink to its normal position as liquid drawn into the bottom of counting cylinder 80 slowly leaks through the relatively small clearance between the counting piston and its cylinder. However, if the overload causing initial opening of the circuit on the particular pole unit persists upon first automatic reclosing of the contacts of such unit, it will immediately reopen its circuit, and this time pawl 86 will engage the next lower ratchet portion 84 of the counting piston and raise the latter a further amount. It will thus be observed that counting piston 82 will be progressively advanced only in response to closely successive operations of its pole unit, to thus indicate by its position the number of such operations. Moreover, counting piston 82 will not count operations of its pole unit which are spaced apart widely enough in point of time to permit the counting piston to reset to its normal position.

The actuating levers 52 for the contact rods of pole units 18 and 20 are located within U-shaped members 92, respectively, which have the leg portions thereof pivotally mounted on pivot shaft 56. It will be observed that pivot shaft 56 is supported at its ends by journal brackets 55 which are substantially U-shaped in section with the bight portions thereof secured to mounting plate 6, and having bearing openings in its arms for supporting pivot shaft 56. Within each U-shaped member 92, there is provided a contact closing spring 94 having one end 96 reacting against the bight portion of its member 92, and the other end 98 thereof reacting against its actuating lever 52 to bias the latter in a clockwise direction (Fig. 1) and thus bias movable contact 40 into engagement with fixed contact 38 of the corresponding pole units 18 and 20. Pole unit 16 has its actuating lever 54 located within a U-shaped member 99, and this, in turn, has a closing spring 100 located therein about pivot shaft 56, which reacts between the bight portion of U-shaped member 99 and actuating lever 54 to bias the latter in a counterclockwise direction (Fig. 1) to bias movable contact 40 of pole unit 16 into engagement with its fixed contact

38. The U-shaped member 99 for pole unit 16 is also pivotally mounted on pivot shaft 56 as are the members 92 for pole units 18 and 20.

In order to actuate the contacts of all of the 5 pole units to an open circuit position and hold them in such a position, a lock-out spring 102 is provided in cover 10 which reacts between a stationary U-shaped bracket 104 mounted on supporting plate 6, and a washer 106 pinned to an actuating link 108 slidably mounted through bracket 104. It will be observed that lock-out spring 102 biases actuating link 108 to the right, as viewed in the drawings, but this spring is normally held inactive in compressed condition by 15 mechanism which will now be described.

Actuating link 108 is pivotally connected to U-shaped member 99 for pole unit 16 as by a pivot bolt 110, and is connected to the other U-shaped members 92 by a link 112 pivoted to link 108 as at 114, and to the U-shaped members by a shaft 116 connecting both U-shaped members 92 and pivotally extending through the lower end of connecting link 112. A link 118 is also pivoted to one arm of U-shaped member 99 at 120, and at its other end has a common pivot 122 for a guide link 123 and a toggle lever 128. Guide link 123 is pivoted on a stationary bracket 126 mounted on supporting plate 6 as at 124, and toggle lever 128 is connected by a knee pivot pin 130 to a second toggle lever 132 which, in turn, is mounted on a fixed pivot 134 supported on a mounting bracket 140 welded or otherwise secured on one supporting bracket 8 for plate 6. Toggle lever 132 preferably has an integral handle extension 136 which extends through a reduced opening in cover 10 and normally engages a stop screw 138 also mounted on bracket 140, beneath an integral hood portion 139 of cover 10, where the handle extension 136 is normally concealed from view.

In the position of toggle levers 128 and 132 illustrated in Fig. 1, knee pivot 130 is below a line connecting their end pivot points 122 and 134, so that lockout spring 102 is prevented from moving actuating link 108 to the right, or U-shaped member 99 clockwise about pivot shaft 56, or connecting link 118 to the left, because toggle knee pivot pin 130 is prevented from moving any further below center by engagement of handle extension 136 with stop screw 138. Moreover, U-shaped members 92 for pole units 18 and 20 are likewise held at the positions shown in Figs. 1 and 2 by virtue of their connection with actuating link 108 through connecting links 112. Accordingly, in the position of the parts shown in Figs. 1 and 2, the contacts of the pole units, either individually or collectively, are free to be automatically separated to open the circuit, and they will be automatically closed following a circuit opening operation by their respective closing springs 94 and 100 inasmuch as the reaction points of such springs, comprising U-shaped members 92 and 99, are held stationary as described above. However, the contacts of all of the pole units may be manually opened by pulling handle extension 136 downwardly to thus move toggle knee pivot pin 130 upwardly over center, whereupon lockout spring 102 is freed to move actuating link 108 to the right, to rotate U-shaped member 99 in a clockwise manner, so that the bight portion thereof engages the upper end of actuating lever 54 for pole unit 16 to open contact 40 of that pole unit, and by virtue of connecting link 112, and connecting shaft 116 between U-shaped members 92, the latter are

moved in a counterclockwise direction so that their bight portions engage the upper ends of their respective actuating levers 52 to thus open the movable contacts 40 of pole units 18 and 20. Of course, lock-out spring 102 in addition to opening the circuit through all of the pole units, will also hold the movable contacts of all the pole units at open circuit positions.

Following a manual opening of the circuits through all of the pole units, the contacts of all units may be manually closed merely by moving handle extension 136 upwardly to move toggle knee pivot pin 130 downwardly overcenter back to the position shown in Fig. 1, where U-shaped members 92 and 99 are returned to the positions shown in Figs. 1 and 2 where they may again furnish reaction points for closing springs 94 and 100, which then become effective to reclose the contacts of their respective pole units. It will be observed that when handle extension 136 has been moved downwardly to open the circuit, it will then occupy a position where it projects from beneath hood 139, to thus give a clear visible indication of the open circuit condition of all poles of the breaker.

In order to provide for automatic opening of the contacts of all poles in response to a predetermined number of closely successive operations of any one or more poles, there is provided a substantially triangular release plate 142 which is supported beneath supporting plate 6 by means of a plurality of supporting links 144 pivotally connected to brackets 146 at the top of release plate 142, and extending through openings at their upper ends to be pivotally mounted as at 148, on supporting plate 6. Links 144 thus support release plate 142 for up and down swinging movement while maintaining release plate 142 substantially in a horizontal position. An actuating rod 150 is secured at the apex of release plate 142 adjacent the wall of tank 2 as by being threadedly mounted through an opening in the plate, and is secured at a longitudinally adjusted position by a lock nut 152. Actuating rod 150 extends up through an opening in supporting plate 6, and has a stop pin 154 extending therethrough to define the lowermost position of release plate 142. The upper end of actuating rod 150 normally lies adjacent to but just beneath toggle knee pivot pin 130.

It will now be observed that whenever counting piston 82 for any one of pole units 16, 18 or 20 is advanced upwardly as the result of a predetermined number of closely successive operations of its pole unit, preferably three or four operations, to engage release plate 142 and move it upwardly, that such upward movement of release plate 142 will cause its actuating rod 150 to also move upwardly into engagement with toggle knee pivot pin 130 and move the latter upwardly over-center to release lock-out spring 102 and permit it to open the contacts of all of the pole units and hold them in such open position, just as when it was released by operation of handle 136, as previously described.

It can thus be seen that this invention contemplates automatic circuit opening and closing of any pole of a multi-pole automatic reclosing circuit breaker entirely independent of operation of the contacts of the other poles of the circuit breaker. However, the invention further provides an arrangement for opening the contacts of all poles of such a circuit breaker in automatic fashion in response to the occurrence of a predetermined number of closely successive

operations of the contacts of any single pole of the breaker. Moreover, the particular arrangement of the parts is such that the contacts and all of their operating mechanism are supported in a unitary fashion in a tank and its cover, from the top rim of the tank, and is secured in position by securement of the cover to the tank.

Having described a preferred embodiment of the invention in accordance with the Patent Statutes, it is desired that the invention be not limited to this particular construction, inasmuch as it is obvious that it may be applied to multi-pole breakers having more or less than 3 poles, and even differing in the particular pole structures and operating mechanism from that particularly disclosed here. Accordingly, it is desired that the invention be interpreted as broadly as possible.

I claim as my invention:

1. A multi-pole automatic reclosing circuit breaker comprising, a plurality of pole units disposed in a common tank and each having separable contacts which are biased into engagement and electro-responsive means for separating the contacts so that the contacts of any pole unit may automatically open and close its circuit independently of the contacts of the other pole units, a single lock-out means having a common releasable means for maintaining it normally inactive but having elements including a single lockout spring to prevent closing of the contacts of all of the pole units when said lock-out means is activated, each of said pole units having counting means advanced by closely successive operations of its unit, said lock-out means having a part actuated by the advance of the counting means of said pole units, respectively, for releasing said releasable means and activating said lock-out means and thus preventing closing of the contacts of all pole units in response to a predetermined number of closely successive operations of any one of said pole units.
2. A multi-pole automatic reclosing circuit breaker comprising, a plurality of pole units disposed in a common tank and each having separable contacts which are biased into engagement and electro-responsive means for separating the contacts so that the contacts of any pole unit may automatically open and close its circuit independently of the contacts of the other pole units, a single lock-out means having inactivating means normally making it inactive but having elements including a single biasing means to prevent closing of the contacts of all of the pole units when said lock-out means is activated, each of said pole units having counting means advanced by closely successive operations of its unit, said lock-out means having a common part actuated by the advance of the counting means of said pole units, respectively, for activating said lock-out means and thus preventing closing of the contacts of all pole units in response to a predetermined number of closely successive operations of any one of said pole units, and an operating handle connected with said lock-out means for operating the latter to active and inactive conditions.
3. A multi-pole automatic reclosing circuit breaker comprising, a plurality of pole units each having separable contacts which are biased into engagement and electro-responsive means for separating the contacts so that the contacts of any pole unit may automatically open and close its circuit independently of the contacts of the other pole units, a single lock-out spring for

actuating contacts of all of said pole units to open circuit position and holding them there against their closing bias, a common releasable holding means normally holding said lock-out spring at an inactive position where it does not interfere with operation of said contacts, each of said pole units having counting means advanced by closely successive operations of its unit, said holding means having a part actuated by the advance of the counting means of said pole units, respectively, for releasing said releasable holding means and thus permit said lock-out spring to move and hold the contacts of all of said pole units at open circuit position in response to a predetermined number of closely successive operations of any of said pole units.

4. A multi-pole automatic reclosing circuit breaker comprising, a plurality of pole units each having separable contacts which are biased into engagement and electro-responsive means for separating the contacts so that the contacts of any pole unit may automatically open and close its circuit independently of the contacts of the other pole units, a single lock-out spring for actuating contacts of all of the pole units to open circuit position and holding them there against their closing bias, a single releasable holding means normally holding said lock-out spring at an inactive position where it does not interfere with operation of said contacts, each of said pole units having counting means advanced by closely successive operations of its unit, said holding means having a part actuated by the advance of the counting means of said pole units, respectively, for releasing said holding means and thus permit said lock-out spring to move and hold the contacts of all of said pole units at open circuit position in response to a predetermined number of closely successive operations of any of said pole units, and an operating handle connected with said lock-out spring and holding means for operating the spring and holding means to release and to reset said spring.

5. A multi-pole automatic reclosing circuit breaker comprising, a metal tank having an open top and a cover for the top, a plurality of spaced pole units supported from the top of said container, each of said pole units including separable contacts which are biased closed and electro-responsive means for separating the contacts so that the contacts of any pole unit may be operated to automatically open and close its circuit independently of the contacts of the other pole units, a single lock-out means which is normally inactive but having elements including only a single biasing means to prevent closing of the contacts of all of the pole units when said lock-out means is activated, each of said pole units having a counting member which is advanced from its normal position a predetermined amount in response to each operation of its pole unit, means for slowly resetting each counting member to its normal position whereby each of said counting members will be advanced an amount greater than said predetermined amount only by a plurality of closely successive operations of its pole unit, a common movably mounted activating member having a portion positioned in advance of said counting members, respectively, a distance greater than said predetermined amount so as to be engaged and moved by any of said counting members in response to a predetermined number of closely successive operations of its pole unit, and means for activating said lock-out means in response to such movement of said ac-

tivating member to thus prevent closing of the contacts of all of said pole units.

6. A multi-pole automatic reclosing circuit breaker comprising, a metal tank having an open top and a cover for the top, a plurality of spaced pole units supported from the top of said container, each of said pole units including separable contacts which are biased closed and electro-responsive means for separating the contacts so that the contacts of any pole unit may be operated to automatically open and close its circuit independently of the contacts of the other pole units, a single lock-out means having a common toggle mechanism for making it normally inactive but having elements to prevent closing of the contacts of all of the pole units when said lock-out means is activated, each of said pole units having a counting member which is advanced upwardly from its normal position a predetermined amount in response to each operation of its pole unit, means retarding resetting movement of each counting member to its normal position whereby each of said counting members will be advanced an amount greater than said predetermined amount only by a plurality of closely successive operations of its pole units, a movably mounted activating member common to all the counting members having parts positioned above said counting members, respectively, a distance greater than said predetermined amount so as to be engaged and moved by any of said counting members in response to a predetermined number of operations of its pole unit, and means for actuating said toggle mechanism and activating said lock-out means in response to such movement of said activating member to thus prevent closing of the contacts of all of said pole units.

7. A multi-pole automatic reclosing circuit breaker comprising, a metal tank having an open top and a cover therefor, said tank being substantially circular in cross section, a plurality of pole units supported from the top of said tank in spaced relation about the interior of said tank, each of said pole units including separable contacts which are biased closed and electro-responsive means for separating the contacts so that the contacts of any pole unit may be operated to automatically open and close its circuit independently of the contacts of the other pole units, a single lock-out means having a common releasable means making it normally inactive but having elements to prevent closing of the contacts of all of the pole units when said lock-out means is activated, each of said pole units having a counting member which is advanced from its normal position a predetermined amount in response to each operation of its pole unit, means for slowly resetting each counting member to its normal position whereby each of said counting members will be advanced an amount greater than said predetermined amount only by a plurality of closely successive operations of its pole units, a movably mounted activating member common to all the counting members having parts positioned in advance of said counting members, respectively, a distance greater than said predetermined amount so as to be engaged and moved by any of said counting members in response to a predetermined number of closely successive operations of its pole unit, and means for releasing said releasable means and activating said lockout means in response to such movement of said activating member to thus prevent closing of the contacts of all of said pole units.

8. A multi-pole automatic reclosing circuit breaker comprising, a plurality of pole units each having separable contacts which are biased into engagement and electro-responsive means for separating the contacts so that the contacts of any pole unit may automatically open and close its circuit independently of the contacts of the other pole units, a single lock-out spring for actuating contacts of all of the pole units to open circuit position and holding them there against their closing bias, a single overcenter toggle means normally holding said lock-out spring at an inactive position where it does not interfere with operation of said contacts, each of said pole units having counting means advanced by closely successive operations of its unit, a movable member positioned to be actuated by each of said counting means in response to a predetermined number of closely successive operations of its corresponding pole unit to move said toggle means overcenter and release said lock-out spring to thus permit it to move and hold the contacts of all of said pole units at open circuit position in response to a predetermined number of closely successive operations of any of said pole units.

9. A multi-pole automatic reclosing circuit breaker comprising, a plurality of pole units each having separable contacts which are biased into engagement and electro-responsive means for separating the contacts so that the contacts of any pole unit may automatically open and close its circuit independently of the contacts of the other pole units, a single lock-out spring for actuating contacts of all of the pole units to open circuit position and holding them there against their closing bias, a common overcenter toggle means normally holding said lockout spring at an inactive position where it does not interfere with operation of said contacts, each of said pole units having means for counting closely successive operations of its unit, movable means positioned to be engaged and actuated by any one or more of said counting means in response to a predetermined number of closely successive operations of its corresponding pole unit to move said toggle means overcenter and release said lock-out spring to thus permit it to move and hold the contacts of all of said pole units at open circuit position in response to a predetermined number of closely successive operations of any of said pole units, and an operating handle connected to one link of said toggle means for operating the latter and the lock-out spring to reset and release said spring.

10. A multi-pole automatic reclosing circuit breaker comprising, a plurality of pole units each having separable contacts which are biased into engagement and electro-responsive means for separating said contacts, an operating lever movable with a movable contact of each pole unit, all of said operating levers being mounted on a common pivot axis which is substantially equidistant from said units, lock-out means also mounted for pivotal movement on said common axis, means biasing said lock-out means into engagement with said operating levers to move said levers to open the contacts of all of said units, releasable means normally holding said lock-out means out of the normal range of movement of said operating levers, and means responsive to a plurality of closely successive operations of the contacts of any of said pole units to release said holding means.

11. A multi-pole automatic reclosing circuit breaker comprising, a plurality of pole units each

having separable contacts and electro-responsive means for separating said contacts, an operating lever movable with a movable contact of each pole unit, all of said operating levers being mounted on a common pivot axis which is substantially equidistant from said units, lock-out means also mounted for pivotal movement on said common axis, means biasing said lock-out means into engagement with said operating levers to move said levers to open the contacts of all of said units, releasable means normally holding said lock-out means out of the normal range of movement of said operating levers, individual means for the contacts of each pole unit for biasing the contacts closed, said biasing means reacting between the operating lever of its pole unit and said lock-out means, and means responsive to a plurality of closely successive operations of the contacts of any of said pole units to release said holding means.

12. A multi-pole automatic reclosing circuit breaker comprising, a plurality of pole units each having separable contacts which are biased into engagement and electro-responsive means for separating said contacts, an operating lever movable with a movable contact of each pole unit, all of said operating levers being mounted on a common pivot axis which is located between at least two pole units of said breaker and is substantially equidistant from all of said units, lock-out means also mounted for pivotal movement on said common axis, means biasing said lock-out means into engagement with said operating levers to move said levers to open the contacts of all of said units, releasable means normally holding said lock-out means out of the normal range of movement of said operating levers, and means responsive to a plurality of closely successive operations of the contacts of any of said pole units to release said holding means.

13. A multi-pole automatic reclosing circuit breaker comprising, a metal tank having an open top and a cover therefor, a supporting member extending across said tank and being supported from the top of said tank, a plurality of pole units supported in spaced relation in said tank from said supporting member, each of said pole units including separable contacts which are biased closed and electro-responsive means for separating the contacts so that the contacts of any pole unit may be operated to automatically open and close its circuit independently of the contacts of the other pole units, a single lock-out means which is normally inactive but having elements to prevent closing of the contacts of all of the pole units when said lock-out means is activated, each of said pole units having a counting member which is advanced from its normal position a predetermined amount in response to each operation of its pole unit, means for slowly resetting each counting member to its normal position whereby each of said counting members will be advanced an amount greater than said predetermined amount only by a plurality of closely successive operations of its pole units, a movably mounted activating member common to all of the counting members and having parts positioned in advance of said counting members, respectively, a distance greater than said predetermined amount so as to be engaged and moved by any of said counting members in response to a predetermined number of operations of its pole unit, means for activating said lock-out means in response to such movement of said activating member to thus prevent closing of the contacts of

all of said pole units, and said lock-out means also being supported in said tank on said supporting member.

14. A multi-pole automatic reclosing circuit breaker comprising, a metal tank having an open top and a cover therefor, a supporting member extending across said tank and being supported from the top of said tank, a plurality of pole units supported in spaced depending relation in said tank from said supporting member, each of said pole units including separable contacts which are biased closed and electro-responsive means for separating the contacts so that the contacts of any pole unit may be operated to automatically open and close its circuit independently of the contacts of the other pole units, a single lock-out means which is normally inactive but having elements to prevent closing of the contacts of all of the pole units when said lock-out means is activated, each of said pole units having a counting member which is advanced from its normal position a predetermined amount in response to each operation of its pole unit, means for slowly resetting each counting member to its normal position whereby each of said counting members will be advanced an amount greater than said predetermined amount only by a plurality of closely successive operations of its pole units, a movably mounted activating member common to all of the counting members, said actuating member having parts positioned in advance of

said counting members, respectively, a distance greater than said predetermined amount so as to be engaged and moved by any of said counting members in response to a predetermined number of operations of its pole unit, means for activating said lock-out means in response to such movement of said activating member to thus prevent closing of the contacts of all of said pole units, and said lock-out means also being supported in said tank on top of said supporting member.

JAMES M. WALLACE.
